H. M. GREEN

ONE-PIECE PLUNGER BODY

Original Filed July 20, 1925

INVENTOR:
Henry M. Green,
BY G. E. Maynard
ATTORNEY

UNITED STATES PATENT OFFICE.

HENRY M. GREEN, OF LOS ANGELES, CALIFORNIA; PACIFIC SOUTHWEST TRUST & SAVINGS BANK, ADMINISTRATOR OF SAID H. M. GREEN, DECEASED, ASSIGNOR TO PATRICK H. BRAY.

ONE-PIECE PLUNGER BODY.

Application filed July 20, 1925, Serial No. 44,851. Renewed May 31, 1927.

This invention relates to plunger pumps and especially to the plungers thereof.

In the present invention my aim is to provide a plunger of simplest construction and 5 fewest parts and yet obtain an effective lifting stroke.

An object is to provide a packing medium which is free on the plunger, has no actuating spring and which is made effective by 10 the load lifted up on the up stroke of the plunger.

An object is to provide a one-piece plunger body and a series of spaced stacks of packing rings therealong each acting independently of the other.

Other objects and advantages will be made manifest in the following specification of an embodiment of the invention here illustrated; it being understood that modifications, 20 variations and adaptations may be resorted to within the spirit of the invention and its scope as it is here claimed.

Figure 1 is a longitudinal section of the plunger in its barrel.

Figure 2 is a plan of one of the packing rings.

The plunger, which is shown as in a barrel B, has a tubular body 2 whose upper end is threaded to receive a valve cage C of any 30 appropriate type.

At suitable distances along the body 2 are circumferential shoulders 3 nearly touching the barrel surface and forming top end stops for subjacent stacks of packing rings 35 4, each of which is split so as to be passed around the body and internally closing on the body.

Above each shoulder 3 the body is of conical form 5 flaring toward its base shoulder 3 so that as the imposed packing rings 4 externally, or peripherally, wear and move down on the wedge part they are expanded out against the barrel. The conical part 5 merges into a cylindrical part 6 along which lies a reserve part of the stack of rings 4.

The bottom of the plunger may have a working valve V under a stop pin 10.

The action of the plunger is as follows:

When working in the barrel B, the up stroke of the plunger will lift the column of liquid and a part of the load weight is taken

up by the exposed, upper packing rings in the different stacks. This load imposed on the packing drives it down onto the expanding wedge or conical parts 5 which at once 55 thrust the near rings 4 outward toward the barrel. On a reverse or down stroke of the plunger the free packing may slide or tend to slide (relatively) on the plunger body toward the shoulder 3. On the up stroke 60 the packing again picks up the load and is forced out against the barrel by the conical body portions and made effective to prevent leak past the plunger.

All springs are eliminated and the body 2 65 consists of but one piece having integral spaced shoulders and wedges to expand the packing rings when these take up the load.

What is claimed is:

1. A pump plunger having a one piece 70 tubular body having cylindrical portions provided with longitudinally spaced, annular, external shoulders and conical base portions opposed to the shoulders, and stacks of packing arranged between the shoulders and 75 expansively acted upon by the said conical portions under load; said packing being free to work between the shoulders as the packing wears down.

2. A pump plunger having a one piece 80 tubular body provided with longitudinally spaced, annular, external shoulders and conical base portions opposed to the shoulders, and stacks of packing arranged between the shoulders and expansively acted upon by 85 the said conical portions under load: said packing being free to work between the shoulders as the packing wears down; the body including cylindrical portions between the shoulders and the conical portions for 90 reserve packing not on the conical portions.

3. A pump plunger having a tubular body provided with longitudinally spaced, annular, external shoulders having stop faces on one side and having conical bases curved out to the rims of the shoulders on the opposite side, and stacks of packing freely movable 95 on the body between opposed shoulders and conical base portions and expanded by the latter.

HENRY M. GREEN.
